LEROY STEWART FOLTZ, OF FORT COLLINS, COLORADO, ASSIGNOR OF ONE-HALF TO
VERNON E. BLAKE, OF FORT COLLINS, COLORADO.

AUTOMATIC TURN-OFF SWITCH.

Application filed February 25, 1920. Serial No. 361,082.

To all whom it may concern:

Be it known that I, LEROY S. FOLTZ, a citizen of the United States, and a resident of Fort Collins, in the county of Larimer and State of Colorado, have invented certain new and useful Improvements in Automatic Turn-Off Switches, of which the following is a specification.

My invention is an improvement in automatic turn-off switches, and the invention has for its object to provide a switch of the character specified adapted for interpolation in electric lighting or heating circuits, and controlled by the passage of the current for shutting off said current at the end of a predetermined time, wherein the switch mechanism is controlled by a movable member, which is connected to an expansion chamber containing a fluid capable of being expanded by heat, which moves said movable member when it expands to open the circuit.

In the drawings:

Figure 1 is a plan view of the improved switch;

Figures 2 and 3 are sections on the lines 2—2 and 3—3, respectively, of Figure 1;

Figure 4 is a view looking from the outer side of one of the terminals.

In the present embodiment of the invention a suitable base is provided, consisting of a ring 1 of insulating material, and a disk 2 which closes the ring. This disk forms one of the walls of the expansion chamber, the other being formed by a substantially cone shaped member 3 of corrugated sheet metal, capable of being expanded and contracted to vary the distance between the apex of the cone and the center of the base.

The large end of this cone 3 is secured to the disk 2, and the said disk has a central enlargement 4 which is a support for a heater. This heater comprises a heating element 5 arranged within the chamber and having its terminals connected with lead wires 6 and 7 which are held in insulating plugs 8 threaded into openings in the enlargement 4.

A movable member or operating handle 9 is connected with the small end of the wall 3, the said wall having a cup shaped member 10 into which the end of the handle is threaded, and a set screw 11 is threaded

through the cup shaped member into engagement with the handle.

A case, consisting of a body 12 and a head 13, is provided for enclosing the working parts, the body being tapered, as shown, and having its large end connected to the ring 1, while the head 13 is connected to the small end, and the handle 9 is slidable through a central opening in the head 13. A pair of latches 14 is pivoted between one pair of yokes 15 held in the casing 12—13, the said latches being pivoted intermediate their ends and having fingerpieces extending through the head 13. The inner ends of the latches have cross pins 16 which are connected by coil springs 17, the said springs being arranged at opposite sides of the handle, as shown.

The ends of the yokes 15 are secured to insulating blocks 18 held in the casing and secured to the body 12, as shown, and to these blocks are also secured contact plates 19, to which are connected lead wires 20 and 7. The lead wire 20 is connected with the lighting circuit as is also the lead wire 6, and it will be seen from the arrangement that the heating element and the switch mechanism to be described are in series in the circuit.

Each latch has a lateral outwardly extending extension 21 and contact members 22 are secured to these extensions, the said contact members being adapted to engage and move upon the contact plates 19. Each latch has also an inwardly extending lug 23 on the inner side of its pivotal connection, and these lugs are adapted to engage a ring 24 which is held on an annular enlargement on the handle.

The operation of the device is as follows:

When it is desired to turn on the lights the finger latches are pressed together, and the operating handle 9 springs inwardly, being pulled inwardly by the resiliency of the corrugated cone 3. The pressing of the latches 14 together closed the circuit, inner ends of the latches are held outwardly by the ring 24, and the contact members 22 are held in engagement with the contact plates 19, thus holding the circuit closed.

With the passage of the current the heating member 5 increases the temperature of the confined gas or liquid, causing the expansion cone to push slowly outwardly, car-

rying with it the handle member 9. After the lapse of an interval of time the handle member moves outwardly far enough to cause the ring 24 to pass beyond the lugs 23 5 and the inner ends of the latches swing inwardly, moving the contact members 22 out of engagement with the contact plates, and opening the circuit.

As soon as the lugs slip from the ring 10 the circuit is opened and the lights are cut off. As the expansion element cools the cone tends to contract, but the handle member cannot return to inward position because it is held by the engagement of the lugs 23 with 15 the inner edge of the ring, as indicated in Figure 2. The circuit will remain open until the operating latches are pressed together at their outer ends.

To manually open the circuit it is only 20 necessary to pull outwardly on the knob of the handle member. The improved switch may be used manually in the same manner as the usual snap switch. When the latches are pressed together the lights are turned on. 25 To turn the lights off the handle member is pulled outwardly. Should one forget to turn off the lights the switch will act automatically, turning off the lights, after a certain length of time. The device is especially 30 valuable on circuits where lights are used for only short intervals, as in cellars, furnace rooms, store rooms, attics and out-buildings. It will be understood that with changes 35 which will be obvious the switch might be made a double pole switch.

I claim:

1. A switch adapted to be interposed in an electrical circuit, said switch comprising contact plates with which the terminals of 40 the circuit are connected, latch members having contact members for engaging the contact plates and normally spring pressed toward each other to cause the contact members to disengage the plates, a movable member movable between the latch members and having a conducting ring for connecting said latch members to complete the circuit and having an enlargement on which the ring is arranged to force said latch members 45 outwardly to close the circuit, and an expansible casing to which the movable member is connected to be moved by the expansion and contraction of the casing, and a heating element interposed in the circuit and 50 arranged within the expansion casing.

2. A switch of the character specified having contact plates spaced apart from each other for connection with the terminals of a circuit, a heating element carried by the 55 switch and interposed in the circuit when the contact plates are connected with the terminals, a pair of latches having contact members for engaging the plates and arranged between the plates and normally 60 spring pressed away from the plates and to-

ward each other, a sliding member movable between the latches and having means for moving said latches apart to cause the contact members to contact with the contact plates and for electrically connecting said contact members, and an expansion chamber in which the heating element is interposed and connected to the movable member to move the same when the chamber is expanded. 70

3. A switch of the character specified comprising an expansion chamber, a heating element in the chamber, a normally operative circuit breaker adapted to be interposed with the heating element in an electrical circuit 80 to be controlled, means controlled by the expansion chamber when in contracted position for restraining the operation of the circuit breaker from breaking the circuit and released by the expansion of the chamber, 85 releasable means in connection with the circuit breaker for holding the chamber from contracting after it has been expanded to break the circuit, and manually controlled means for expanding the chamber. 90

4. A switch of the character specified comprising an expansion chamber, a heating element in the chamber, a normally operative circuit breaker adapted to be interposed with the heating element in an electrical circuit 95 to be controlled, means controlled by the expansion chamber when in contracted position for restraining the operation of the circuit breaker from breaking the circuit and released by the expansion of the chamber, and 100 releasable means in connection with the circuit breaker for holding the chamber from contracting after it has been expanded to break the circuit.

5. A switch of the character specified, 105 comprising a thermostat and a circuit breaker adapted to be interposed in an electrical circuit, said circuit breaker being normally spring controlled to break the circuit, means in connection with the circuit 110 breaker and controlled by the thermostat for preventing the operation of the circuit breaker to break the circuit until a predetermined degree of heat is attained at the thermostat, and means in connection with the 115 circuit for preventing the thermostat from operating the circuit breaker to close the circuit after the circuit has been broken, said means being releasable.

6. A switch of the character specified, 120 comprising contact plates spaced apart from each other for connection with the terminals of a circuit, contact members mounted to move into contact with the plates to close the circuit and to move toward each other 125 to open the circuit and normally spring drawn together, a heating element adapted to be interposed in the circuit and expansible under heat and having means in connection therewith and moving between the contact 130

members for holding them apart until the heating element is heated to a predetermined degree.

7. A turn off switch comprising a control handle, a heat operated member for actuating said control handle, a latch associated with said handle and having a hand grip forming a means whereby the latch may be operated, stationary and movable contacts associated with said latch, there being means between the control handle and the latch for holding said stationary and movable contacts in engagement with each other during the inactivity of said heat controlled member, said heat controlled member being adapted to move said handle and said means whereby to break the connection between the stationary and movable contacts when the heat exceeds a predetermined degree.

8. A turn off switch comprising a control handle, a heat operated member for actuating said control handle, a latch associated with said handle and having a hand grip, forming a means whereby the latch may be operated, stationary and movable contacts associated with said latch, there being means between the control handle and the latch for holding said stationary and movable contacts in engagement with each other during the inactivity of said heat controlled member, said heat controlled member being adapted to move said handle and said means whereby to break the connection between the stationary and movable contacts when the heat exceeds a predetermined degree, said second means consisting of enlargements formed on the opposed sides of said handle and said latch.

9. A turn off switch comprising a control handle, a heat operated member for actuating said control handle, a latch associated with said handle and having a hand grip, forming a means whereby the latch may be operated, stationary and movable contacts associated with said latch, there being means between the control handle and the latch for holding said stationary and movable contacts in engagement with each other during the inactivity of said heat controlled member, said heat controlled member being adapted to move said handle and said means whereby to break the connections between

the stationary and movable contacts when the heat exceeds a predetermined degree, and a casing receiving said heat controlled member and the adjacent portion of said handle and the major portion of said latch, the rear portion of said handle and the hand grip of said latch being extended exteriorly of said casing.

10. A turn off switch comprising a control handle, a heat operated member for actuating said control handle, a pair of latches associated with said handle and having hand grips, stationary and movable contacts associated with said latches, there being means between the control handle and the latches for holding said stationary and movable contacts in engagement with each other during the inactivity of said heat controlled member, said heat controlled member being adapted to move said handle and said means to a predetermined point whereby to break the connection between the stationary and movable contacts, and spring means connecting said latches.

11. A switch comprising a longitudinally movable handle having an enlargement, latches having lugs engaged by said enlargement, spring means for urging said lugs into engagement with said enlargement, contacts associated with said latches, and a heat operated means for actuating said handle.

12. A switch comprising a longitudinally movable control handle having an enlargement intermediate its ends, latches pivoted intermediate these ends and having lugs, spring means for urging said lugs into engagement with said enlargement, stationary contacts, and relatively movable contacts carried by said latches.

13. A switch comprising a longitudinally movable control handle having an enlargement intermediate its ends, latches pivoted intermediate these ends and having lugs, spring means for urging said lugs into engagement with said enlargement, stationary contacts, relatively movable contacts carried by said latches, and automatic means connected to the forward ends of said handle for moving the handle longitudinally.

LEROY STEWART FOLTZ.
